US0D1085021S

(12) **United States Design Patent** (10) **Patent No.:** **US D1,085,021 S**
Maranto (45) **Date of Patent:** **** Jul. 22, 2025**

(54) **ELECTRICAL RECEPTACLE WITH IN-LINE POWER UNIT**

(71) Applicant: **Group Dekko, Inc.**, Fort Wayne, IN (US)

(72) Inventor: **Vincent Maranto**, Fort Wayne, IN (US)

(73) Assignee: **Group Dekko, Inc.**, Fort Wayne, IN (US)

(**) Term: **15 Years**

(21) Appl. No.: **29/811,493**

(22) Filed: **Oct. 14, 2021**

Related U.S. Application Data

(60) Division of application No. 29/723,868, filed on Feb. 11, 2020, now Pat. No. Des. 933,611, which is a continuation-in-part of application No. 29/663,383, filed on Sep. 14, 2018, now Pat. No. Des. 911,975.

CLAIM

The ornamental design for an electrical receptacle with in-line power unit as shown and described.

DESCRIPTION

FIG. 1 is a perspective view of an electrical receptacle with in-line power unit showing my new design;

FIG. 2 is a left side view thereof;

FIG. 3 is a front view thereof;

FIG. 4 is right side view thereof;

FIG. 5 is a back view thereof;

FIG. 6 is a top view thereof; and,

FIG. 7 is a bottom view thereof.

In the drawings, the broken lines are for the purpose of illustrating environmental subject matter and portions of the article that form no part of the claimed design.
